L. E. VAN HISE

INTERNAL COMBUSTION ENGINE

Filed Sept. 3, 1921

UNITED STATES PATENT OFFICE.

LESTER E. VAN HISE, OF LOS ANGELES, CALIFORNIA; SAID VAN HISE ASSIGNOR TO
JAMES V. BALDWIN.

INTERNAL-COMBUSTION ENGINE.

Application filed September 3, 1921. Serial No. 498,434.

This invention relates to internal combustion engines, and particularly to the fuel feed mechanism thereof.

An object of the invention is to provide a novel, simple, and effective apparatus which will be automatic in operation and will require practically no attention to keep it operative.

Another object is to provide a fuel feeding apparatus in which the amount of fuel fed is in direct proportion to the speed of the engine.

A further object is to eliminate the objectionable feeding of unvaporized fuel directly to the intake or to the lubricating mechanism which is necessarily inherent in feeding devices where the fuel feed depends upon suction exerted through a conductor connected between a vacuum tank and the intake or the oil pumping mechanisms of internal combustion engines. In my invention no fuel can reach the engine except through the carburetor, since the fuel feeding conductor begins at the fuel tank and ends at the carburetor and has no bypass, suction pipe, or connection of any kind which could feed fuel to the engine or to any part thereof except through the carburetor.

A further object of my invention is to utilize the energy ordinarily wasted and remaining in fuel after its passage through the engine to cause continuous operation of the fuel feeding mechanism.

With the above mentioned and other objects in view, the invention consists in the novel and useful provision, formation, construction and relative arrangement of the various parts, members and features, as illustrated in one embodiment in the accompanying drawing, described in the following detailed statement, and finally pointed out in claims.

In the drawing:

Figure 1 illustrates an automobile incorporating the improved fluid elevating and feeding means;

Figure 2 is a fragmentary cross sectional view showing the improved elevating and feeding means in its entirety, the same being associated with a well member and having various fluid conduits associated therewith; and,

Figure 3 illustrates a modification of a

certain part of the fluid elevating and feeding means.

Corresponding parts in all the figures are designated by the same reference characters.

Referring now with particularity to the drawing, A designates in its entirety and in one embodiment the fuel elevating and feeding means and B designates a motor vehicle. The motor vehicle B is provided with the usual engine 1 which has an exhaust manifold 2 and carburetor 3 for feeding a fluid to said engine, the carburetor being shown dotted. 4 designates a fuel-supply tank and 5 a fuel conduit joined to said fluid supply tank 4 and having incorporated therewith the improved elevating and feeding means A.

The improved means A includes in one embodiment a valve member *a* and an energizer *b* which may be characterized as a pumping bottle or chamber because it is in effect a closed bottle having a neck in which is located a single opening that provides communication with the interior thereof. The valve member *a* includes a housing 6 formed with spaced chambered portions 7 and 8 with a port 9 communicating with the chambered portions. A valve seating member 10 is detachably joined to one end of the housing and a ball member 11 is adapted to close the annular opening in the member 10, said valve being provided with a compression spring 12 adapted to ensure a closing. The conduit 5 is held to the member 10 and communicates with the annular space of the member 10 as shown at 13. The chamber 8 likewise has a ball member 14 therein with a spring 15 bearing on the surface thereof and the ball 14 is adapted to close the upper portion of the port 9. It will thus be seen that we have two ball check valves which are designated in their entirety as *c* and *d*. The valve member *a* likewise has a chambered portion 16 spaced above the chamber 8 with an inter-communicating port 17 between said chambers. The exterior of the valve member is formed with radiating vanes 18 and the vanes cover an area equal in length to the length of the chamber 16. The energizer *b* includes a shell body 19 provided with bead or flange 20 and an annular neck 21. A port 22 communicates with the annular space included by the neck and with the interior of the

body 19. A projection 23 on the valve member *a* is received within the neck 21 and the port 22 is in communication with a port 24 passing through said member 23 and in 5 communication with the port 9.

In utilizing the device just described the energizer *b* is inserted through an opening 25 in the exhaust manifold 2, and to ensure that the energizer will be retained within 10 the body of the exhaust manifold the energizer *b* is provided with a threaded stud 26 joined to the base thereof and passed through a small opening in the manifold with a nut 27 having a screw-threaded en- 15 gagement with said stud bearing against the periphery of the manifold. As before stated, the conduit 5 communicates with the valve member *a* at one end thereof and the opposite end of said valve member *a* is formed 20 with a reduced portion 28 having a port 29 therein communicating with the chamber 16, and a cap member 30 carrying a fluid conduit 31 is held to the reduced portion 28 by threading the cap thereto or by welding or 25 otherwise, so that the annular space of the conduit 31 is in communication with the port 29.

We may connect the conduit 31 directly with the carburetor 3 or we may incorporate 30 in one embodiment of the invention a well member C. Assuming that the well member C is used, which well member may comprise 35 a small tank having a cylindrical shell 32 with a top member 33 and a base member 34 held thereto, the conduit 31 would be connected to the top plate member 33. It is 40 intended that the well member C be joined with the frame of an automobile and above the carburetor as shown in Figure 1. The well member is provided with a conduit 35 passing through the base 34 and communicating with the carburetor 3, and is also provided with an overflow pipe 36 connecting 45 with the conduit 5 as shown at 37. The usual vent opening and its plug 38 is incorporated in the top plate 33.

The operation of the device just described is as follows: If the tank 4 is not high enough to induce flow of gasoline through 50 the conduit 5 past the valve 11 and into the energizer *b*, it will be necessary to prime the energizer with whatever fuel is to be used, such as gasoline. A primer is shown at *e* and the primer includes a priming cup 39 and a valve cut-off 40 with a conduit member 41 communicating with the ports 9 and 24. After the device has been fully primed 55 and the engine started, assuming of course that the carburetor has gasoline within its well, heated gases will be expelled from the engine through the exhaust manifold and these heated gases will heat the shell 19 of the member *b*. Gasoline within the member *b* will then tend to expand and also vaporize 60 and this expansion and vaporization will cause

a pressure against any gasoline tending to pass through the port 24 into the member *b*. The gas formed in the member *b* continues to expand, exerting a pressure upon the surface of the gasoline within the member *b* and forces the gasoline back through the ports 22 and 24 into the chambers 8 and 16. This gas continues to escape past the valve *c* until there is an equilibrium between the pressure within the member *b* and the gas 70 which has been forced therefrom. The cooling and condensation of this gas causes a vacuum which has a tendency to draw more gasoline through the conduit 5 past the valve *d* and into the member *b*, whereupon the 75 cycle of operations just described will be repeated. Obviously the vapor and the gasoline forced ahead of said vapor will have a tendency to boost and elevate the gasoline from the chamber 16 and through the conduit 31 to where it will drop into the well C and fill said well. The gasoline from said well is then fed through the conduit 35 to the carburetor 3 and said conduit 35 may of course be provided with the usual cock. If 80 the gasoline level within the well reaches a determined point said fluid will flow within the pipe 36 and be conducted back to the tank 4.

It will of course be understood that the 85 starting of the apparatus requires an initial full priming so that the pump chamber *b*, the passages 22 and 24, and the chamber 9 between the two check valves 11 and 14 are 90 filled with fluid except for the space left 100 above the plane in the top of passage 22 which provides a vapor chamber. When thus fully primed the application of heat to the pump chamber *b* rapidly vaporizes the 105 pressure thereon which will expel fluid upwardly past the check valve 14, and this vaporization and expulsion of liquid will continue until the pressure above the intake check valve 11 is less than the atmospheric pressure 110 above the fluid supply in the tank with which the pipe 5 connects. When such differential in pressure occurs, atmospheric pressure will force a quantity of cool liquid past the valve 11 into the heated areas *b*, 9, 24 and 22 115 thereby causing rapid condensation due to the cooling effect of the incoming fluid thereby intensifying the vacuum. That condition necessarily provides the force for drawing into the pump chamber *b* a fresh supply 120 of fluid from the pipe 5, and that fresh supply of fluid is in turn vaporized and expelled in the manner already described. This operation repeats itself so as to give a distinct pulsation or pumping action that will pump 125 the fluid in almost a continuous stream into pipe 31 into a well or container C designed to receive the same.

In Figure 3 I have shown a modification *b'* of the energizer *b* and in which the en- 130

ergizer assumes a vertical position in place of the horizontal position shown in Figure 2, with respect to the exhaust manifold.

The energizer *b'* includes a shell 42 having a flanged extremity 43. It also includes the stud 26 with the nut 27 screw-threaded thereon for holding the shell 42 within the exhaust manifold 2. A second shell or container 44 is received within the shell 42 and the periphery of said shell 44 is in spaced relation to the inner surface of the shell 42, as shown at 45. The shell 44 is provided with transverse perforations 46 and 47 for allowing communication between the inner chamber 48 of the shell 42 and the annular space or vapor chamber 45. The stud 23 of the valve member *a* has a screw-threaded engagement with the shell 44 so that the port 24 contained therein may communicate with the chamber 48. This is simply a modification, and the principle of operation, as before described, is the same.

It will thus be seen that I have provided an elevating or boosting and feeding means which will elevate a fluid to a given height and which when used with gasoline-propelled vehicles, provides a simple and economical system for feeding the gasoline to the carburetor at a constant flow irrespective of the angle assumed by the vehicle in its travel, and which will be reliable in all details and which will overcome the necessity of providing complicated structures and devices now generally utilized in feeding gasoline to the carburetor.

It has been found that the lower valve member *d* is the only valve member required to successfully operate the device, and that the member *c* may be eliminated. The valve *d*, however, should be placed as near as possible to the port 24 so that this valve may prevent any back pressure through the line 5.

Experiment has likewise demonstrated that some artificial cooling means such as 45 incorporating water jackets around the valve member *a* materially aids the operation of the device. This water jacket member should have connections so that water or other fluid might be circulated. 50

It is obvious that many changes and variations and modifications may be made in departure from the particular description and showing of the accompanying drawing, in adapting the invention to varying conditions 55 and requirements of use and service, without departing from the true spirit of the invention.

Having thus disclosed my invention, I claim and desire to secure by Letters Patent:

1. In combination with an internal combustion engine having an exhaust duct and a carburetor, a source of fuel supply therefor, a pumping bottle partly seated in said duct, a pipe connecting said source of supply to said bottle, a check valve in said pipe, a storage tank arranged adjacent said carburetor, a pipe connecting said bottle to said tank, an overflow pipe connected to the first 70 named pipe between said check valve and said source of supply, and a pipe connecting said tank and carburetor.

2. In a fuel supply system, the combination of main and auxiliary supply tanks, a 75 conduit connecting said tanks and having check valves spaced apart therein, a heat operated pumping bottle having a single opening and mounted with said opening connected to said conduit between said 80 valves, and an overflow pipe connecting said auxiliary tank with said conduit.

In testimony whereof, I have signed my name to this specification.

LESTER E. VAN HISE.
